UNITED STATES PATENT OFFICE.

ROBERT EDWIN REARDON, OF OTTAWA, ONTARIO, CANADA.

SEALABLE STRAINER-CARTON.

1,315,413.

Specification of Letters Patent.

Patented Sept. 9, 1919.

Application filed September 6, 1916. Serial No. 118,637.

To all whom it may concern:

Be it known that I, ROBERT EDWIN REARDON, of the city of Ottawa, in the county of Carleton, Province of Ontario, and Dominion of Canada, have invented certain new and useful Improvements in Sealable Strainer-Cartons, of which the following is a full description.

This invention relates to improvements in sink garbage strainer cartons, and particularly to such as may be used as sink strainers and which may after use be closed and sealed forming a sanitary paper-cased brick of refuse to be placed in garbage can or elsewhere to await removal.

The general object of the invention is to provide a simple and efficient device of this character, preferably constructed of paper or pulp, waterproofed and made antiseptic and germicidal, which may be neat and sanitary in use, and which may be covered either temporarily when in position, or completely closed when filled with refuse prior to placing in the receptacle for garbage or the fire.

Further objects are to so construct the container that when closed it will form a conveniently handled package adapted to remain closed when placed in the garbage or waste receptacle.

Further objects still are to enable the device to be formed by folding of a single blank of paper or pulp stock, to construct the same of maximum strength, and to support the bottom of the receptacle out of contact with the sink or other receptacle in which it is used.

With these and other objects in view, this invention consists of the improved construction hereinafter described in detail in the accompanying specification and drawings.

In the drawings:

Figure 1 is a perspective view of the container partially closed.

Fig. 2 is a cross sectional view in closed position.

Fig. 3 is a transverse sectional view taken at right angles to Fig. 2.

Fig. 4 is a plan view of the blank from which the receptacle is constructed.

Referring to the drawings, A represents the central or body portion of the carton or container and comprises a blank having a central portion 10, with diametrically opposite pairs of wings, 12, 13, 14 and 15. Each

of the wings 12 and 13 are formed with 55 inner portions 16 and 17 designed to form the sides of the container, and outer portions 18 and 19 adapted to fold downwardly against the portions 16 and 17 to reinforce the same and to form a support for the 60 body portion.

The portions 16 and 17 are formed at the sides with interlocking tabs 20 having notched ends 21 adapted to fit into and engage interlocking slots 23 formed in the 65 inner portions 24 and 25 of the wings 14 and 15.

The inner portions 24 and 25 are adapted to also form part of the inner walls of the container while outer portions 26 and 27 are 70 designed to be folded downwardly to form a support for the body portion of the container, as shown in Figs. 2 and 3.

The outer portions 26 and 27 are each formed with tabs or wings 28 and 29, designed to be folded outside the portions 16 and 17 and inside the outer portions 18 and 19 as shown in Fig. 3, forming side supports for the body portion.

These tabs or wings 28 and 29 are 80 designed to interlock with each other, as for example by the tabs 30 on one tab or wing designed to engage a slot 31 on the other.

The tabs 28 and 29 are formed along the edges which will be the bottom in use, with 85 a series of apertures 33 through which the drainage water may pass.

To further interlock the tabs 28 and 29 on opposite ends with each other, tongues 34 are provided formed by cutting slots 35 90 in the ends of the tab, said tongues being designed to be engaged with corresponding slots 36 formed near the inner edge of the opposite tab.

The carton, in order to adapt it for use as a strainer is formed with a plurality of perforations 50, conveniently arranged in rows as shown. When the container is full of refuse it is desirable to close these holes and to form a completely inclosed container, this is provided for by means of extensions 40 and 41, formed on the outer portions of the wings 14 and 15. These outer portions normally lie against the outer portions 26 and 27, being held in position by means of tongues 42 in the edges of the extensions which engage beneath corresponding tongues 43 formed on the portions 26 and 27.

In order to enable the container to be completely closed, wings 46 are formed on the edges of the extensions 40 and 41 adapted to be bent laterally when said extensions are folded beneath the bottom as shown in dotted lines in Fig. 1. These wings 46 in closed position thus close the apertures 33.

When the outer portions of the wings 12 10 and 13 are bent over the top of the container a tongue 60 is adapted to receive and guide the edge of the opposite wing, and side tongues 61 and 62 are adapted to extend laterally into slots 63 and 64. A further tongue 68 is adapted to receive the edge of the tongue 60 and lock the cover thereby.

To assist in supporting the container in position, by making side wall bottoms more rigid by bend in material and also to form 20 an interlocking retaining strip for the wings 40 and 41 and the tab 46, the slots 47 assisting in the interlocking, feet may be formed by a lateral flange 65 on the portions 28 and 29.

25 The container remains in the position shown in Fig. 3 during use, the refuse water draining through the perforations 50 and the apertures 33.

If it is desired to close the top at any 30 time, the portions 18 and 19 which are normally held down over the side walls formed by 28 and 29, by the tabs 48 engaging in the slots 49 in the latter, may be folded over to lock as shown in Fig. 1.

35 When the container is filled, if it is desired to form it into a closed package before throwing away, the outer portions 18 and 19 are folded over as shown, and pressed down until the tab 60 engages the 40 tab 68 to lock cover, at the same time the extensions 40 and 41 are folded beneath the container and engage with the wall bottom flange 65, as already described and as indicated in dotted lines in Fig. 1.

45 While the container has been described as made of paper, it is to be understood that term paper includes any form of readily foldable pulp material, and any flexible, foldable material which will retain its shape 50 after the manner of paper. Any suitable waterproofing or antiseptic and germicidal composition, or both, may be used if desired, incorporated with the paper or coated on the exterior of the container or blank.

55 It will be found that the waterproofing material will also promote combustion, and this is desirable when the package is eventually consigned to a refuse destroyer.

As many changes could be made in the 60 above construction and many apparently widely different embodiments of my invention within the scope of the claims constructed without departing from the spirit or scope thereof, it is intended that all mat-

ter contained in the accompanying specification and drawings shall be interpreted as 65 illustrative and not in a limiting sense.

What I claim as my invention is:

1. A strainer-carton having a perforated body portion, and wings adapted to form a 70 support for the body portion and extension of said wings to form a closure therefor.

2. A strainer-carton having a perforated body portion and wings adapted to form a support for the body portion and extensions 75 of said wings to form a closure therefor and means on the wings adapted to interlock.

3. A strainer-carton having a perforated body portion, and wings adapted in one position to form a support for the body portion and in another position to form a closure therefor, 80 and means on the wings adapted to interlock in both positions.

4. A strainer-carton having a body portion and wings adapted in one position to 85 form a support for the body portion and in another position to form a closure therefor, one of said wings being formed with a guiding tab adapted to fit over the edge of the opposite wing.

5. A strainer-carton having a body portion and wings adapted in one position to form a support for the body portion and in another position to form a closure therefor, 90 said wings overlapping in closed position 95 and being formed with interlocking means both at the center and at the sides.

6. A strainer-carton having a body portion, and wings adapted in one position to form a support for the body portion and in another position to form a closure therefor, 100 said wings being formed with apertures for the passage of fluid when they are in supporting position.

7. A strainer-carton having a body portion, and wings adapted in one position to form a support for the body portion and in another position to form a closure therefor, the said wings being formed with flanges on the edge adapted to form feet and a winged 110 base for the container and interlock with the closure wings when they are used to seal the carton.

8. An integral paper sink garbage collector and strainer having a body portion 115 and side flanges extending around the same and adapted to support the body portion a distance above the bottom of the sink or the like in which it is placed, said flanges being adapted to fold over the top of the body 120 portion to form a closure for the same and make a completely inclosed garbage package.

9. A strainer-carton formed from a foldable blank formed with four wings arranged in diametrically opposite pairs, each wing being formed with an upstanding portion adapted to form a side of the container, and 125

an outer portion adapted to fold downwardly to form a support for the body portion, said outer portion being adapted to fold over the body portion to form a closure for the container.

10. A strainer-carton formed from a foldable blank formed with four wings arranged in diametrically opposite pairs, each wing being formed with an upstanding portion adapted to form a side of the container, and an outer portion adapted to fold downwardly to form a support for the body portion, said outer portion being adapted to fold over the body portion to form a closure for the container, said wings being formed with suitable slots and tabs whereby they may be interlocked in both positions.

11. A strainer-carton formed from a foldable blank formed with four wings arranged in diametrically opposite pairs each wing being formed with an upstanding portion adapted to form a side of the container, and an outer portion adapted to fold downwardly to form a support for the body portion, said outer portion being adapted to fold over the body portion to form a closure for the container, said wings being formed with suitable tabs and slots whereby they may be interlocked in both positions, one

pair of said wings being formed with extensions adapted to fold over to form a second thickness to the outer supporting portion of the wing.

12. A strainer-carton comprising a perforated bottom, relatively opposite pairs of wings adapted to fold downwardly to form supports for the body portion, certain portions of said wings being formed with perforations providing a drainage portion, the other portion being adapted in one position to close the said drainage apertures.

13. A strainer-carton comprising a perforated bottom, relatively opposite pairs of wings adapted to fold downwardly to form supports for the body portion, certain of said wings being formed with perforations providing a drainage portion, the other wings being adapted in one position to close the said drainage apertures, other of said wings being adapted to fold over the top of the package to form a closure for the same.

In witness whereof I have hereunto set my hand in the presence of two witnesses.

ROBERT EDWIN REARDON.
